FIG. 9 GEORGE H. TAYLOR,
BY *B.P. Johnson*

ATTORNEY

UNITED STATES PATENT OFFICE

2,331,086

TICKET AND TICKET HOLDING DEVICE

George H. Taylor, Norfolk, Va.

Application September 30, 1941, Serial No. 413,023

3 Claims. (Cl. 40—140)

My invention relates to price tickets and holding means for such tickets.

In stores, particularly self-service stores, price tickets are used to indicate the value of the merchandise. These tickets are usually mounted upon moldings which are secured to the edges of the shelves and hence the tickets are held in close relation to the corresponding goods. Such moldings have grooves to receive the edges of the price tickets and the price tickets are adjustable or shiftable within the grooves longitudinally of the molding. As a result of this, considerable inconvenience and errors are caused by the improper or accidental shifting of the price tickets with respect to the merchandise. To overcome this difficulty, the price tickets are sometimes nailed or tacked to the molding, with the result that the tickets as well as the molding are marred or destroyed.

In accordance with my invention, I provide tickets having characters or numerals printed upon the front face only, with or without the value designations, such as the cent mark, or with or without direction indications, such as a hand or arrow pointing toward the goods to which the price applies. The rear faces of the tickets are coated in whole or in part with a pressure-sensitive adhesive, which is permanently plastic or non-drying, such as a rubber cement or rubber compound used on masking tape. This masking tape is frequently employed by painters for holding shields over the surfaces not to be sprayed. This pressure-sensitive adhesive will attach itself to a surface, when subjected to a slight pressure. The price ticket with the pressure-sensitive adhesive applied to its rear face is mounted upon the molding, and the adhesive attaches to the surface of the molding or a strip carried thereby. The pressure-sensitive adhesive attaches to the surface sufficiently to positively prevent the accidental or improper shifting or displacement of the price ticket, but is not permanently attached thereto and will permit the price ticket being separated from the surface, upon proper manipulation. When the price tickets have value indicating characters or direction indicating characters, a portion of one ticket may overlap a portion of the other ticket to cover the characters of one ticket. The two tickets are thus held together for use and the two connected tickets may be mounted upon the molding or secured to an article of merchandise by the same pressure-sensitive adhesive on the back of the two connected tickets.

In the accompanying drawing forming a part

of this application and in which like numerals are employed to designate like parts throughout the same,

Figure 1 is a perspective view of price tickets and a ticket holding device, embodying my invention;

Figure 2 is a transverse section taken on line 2—2 of Figure 1.

Figure 3 is a transverse section through a modified form of molding and price ticket.

Figure 4 is a transverse section through a further modified form of molding and price ticket.

Figure 5 is a rear elevation of one of the price tickets,

Figure 6 shows two of the price tickets arranged in a manner to indicate their overlapping relation whereby one price ticket covers the price indicating and the direction indicating characters of the other price ticket,

Figure 7 shows two of the connected overlapping price tickets secured to an article of merchandise,

Figure 8 is a front elevation of a strip of price tickets having a backing sheet secured to the rear adhesive carrying face of the same, and,

Figure 9 is an elevation of the rear face of the strip of price tickets showing the backing sheet unperforated.

In the drawing, wherein for the purpose of illustration are shown preferred embodiments of my invention, attention being called first to Figures 1 and 2, the numeral 10 designates a molding which may be formed of wood and is preferably of the shape shown in Figures 1 to 4 inclusive of my Patent 1,972,959. This molding has flanges 11 and undercut grooves 12, to receive a resilient strip 13. This resilient strip is preferably laminated and includes a rear cardboard layer 14 and a front Cellophane or Celluloid layer 15, which are secured together. This front layer produces a surface which is dense and smooth. I prefer to bend the strip 13 upon itself at longitudinal lines 16 forming inner tongues 17, arranged within the grooves 11. These tongues 17 are considerably resilient and increase the resiliency of the entire strip 13. The tongues 17 are arranged upon the rear face of the resilient strip 13, between it and the front face of the molding, and serve to space the rear face of the strip from the front face of the molding, thereby providing a space at the rear of the resilient strip so that the resilient strip may be depressed within the space upon the application of pressure to the same. It is desirable that the molding have a surface which is dense and smooth so that the

non-drying adhesive of the price tickets, to be described, will have sufficient attachment to the dense and smooth surface to properly prevent accidental or improper displacement of the price tickets, but will permit of the separation of the price tickets from the smooth surface when desired, without leaving a deposit of the adhesive material upon the smooth surface.

In Figure 3, I have shown a molding 18 which may be formed of glass. This molding has flanges 19 and undercut grooves 20 and a surface 21 which is preferably transversely convex and has a longitudinal groove 22. Since the molding is formed of glass its face 21 provides a dense and smooth surface so that the adhesive of the price ticket will attach itself thereto in the desired manner, as explained in connection with the first form of molding. The groove 22 permits of the insertion of a tool, such as a pencil point, behind the ticket to separate the ticket from the smooth face 21. While it is preferred that the molding 18 be formed of glass it may be formed of other suitable material which would provide a dense and smooth surface 21, such as "Bakelite," or other plastics, or even polished metal.

In Figure 4, I have shown a molding 23 which may be formed of wood having flanges 24 and grooves 25 which are parallel with the face 26. The strip 27 is the same as the strip 13 including the rear cardboard layer 28 and the front Cellophane or Celluloid layer 29. The strip is bent to provide the tongues 30. The tongues 30 are arranged upon the rear face of the resilient strip between it and the front face of the molding and serve to space the rear face of the strip from the front face of the molding thereby providing a space upon the rear face of the strip into which the strip may be depressed when pressure is applied to the front face of the strip. This arrangement affords a surface which is flat and the surface is dense and smooth.

The numeral 31 designates price tickets, which may be formed of cardboard and having characters, such as numerals 32 printed upon their front faces only. The front faces may also be provided with value and direction indicating characters 33 and 34, printed upon the front faces thereof only. It is preferred that the price tickets, after the printing of the same, have their front faces covered with a sheet of transparent Cellophane or Celluloid, and secured thereto, as indicated at 35, for providing a dense and smooth surface or this dense and smooth surface may be provided by coating or spraying the ticket with a cellulose paint, such as cellulose acetate, or the ticket may itself be formed of a material which will provide a dense and smooth surface, such as pyroxyline or Celluloid. Each price ticket 31 for its rear face coated with a pressure-sensitive permanently plastic adhesive 36, such as a rubber cement or rubber compound, used upon masking tape as explained. This adhesive preferably extends over the entire area of the rear face of the ticket, and is capable of repeated applications in attaching the ticket to a surface and removals from such surface and will releasably adhere to smooth surfaces under adverse weather conditions and may be separated from the smooth surface without leaving an adhesive deposit thereon. I may also use the pressure-sensitive adhesive employed upon the ordinary surgical tape. This adhesive 36 is permanently plastic and will adhere to a smooth surface, when subjected to slight pressure.

The numeral 37 designates price tickets which

are identical with the price tickets 31, front and back, except that the indicating characters 33 and 34 are omitted and therefore the tickets 31 are arranged in edge-to-edge relation instead of overlapping.

In the use of the tickets in connection with the molding shown in Figures 1 and 2 and the resilient strip 13, such tickets are placed upon the molding in advance of the strip and their edges 10 are held within the grooves 12. The price ticket is pressed gently against the dense and smooth surface afforded by the strip 13 and the non-drying adhesive 36 will attach the price ticket to the strip 13 so that the price ticket cannot be accidentally shifted longitudinally of the strip 13. However, since the surface afforded by the strip is dense and smooth, the price ticket may be separated from the backing strip by the insertion of the finger nail or a suitable implement between the edges of the price ticket and the strip. Since the backing strip is resilient and since there is a space at its intermediate portion, the connection between the backing strip and the adhesive may also be broken by forcing the strip inwardly. 20 Since the surface of the strip is dense and smooth the non-drying adhesive will not leave a deposit of the cement on such surface upon the separation of the price ticket from the same, thus insuring a clean and attractive surface. Since the 30 glass molding 18 in Figure 3 provides a dense and smooth surface 21, the non-drying cement will attach the price ticket to the same and hold the same against accidental displacement and will permit of the proper separation of the price ticket 35 and the surface 21 without leaving a cement deposit upon such surface. The same is true of the use of the molding 23, Figure 4, and its strip 27 having the dense and smooth surface. The price tickets 37 which do not overlap, are attached by the cement to the dense and smooth surface of the molding. The price tickets 31 may be arranged in overlapping relation so that a portion of one ticket covers the value and direction indicating characters 33 and 34. Thus two price 45 tickets printed "4¢" may be assembled in overlapping relation to produce "44¢." The cement 36 upon the front price ticket will secure this price ticket to the rear price ticket whereby they are attached to produce a unit, without the necessity of slits for interfitting the tickets, such as shown in my Patent No. 1,529,968. The overlapping connected price tickets may be arranged upon the molding 10 and the cement upon the rear sides will attach the same to the dense and smooth surface of the molding. The assembled overlapping price tickets may also be directly mounted upon the goods, as shown in Figure 7, and the cement 36 will secure the same thereto. 55 Since the front faces of the price tickets have a surface which is dense and smooth, when the overlapping price tickets are separated, a cement deposit will not be left upon the front face of the previously rear price ticket.

In the manufacture of the price tickets 31 or 37, it is preferred to print them from a continuous strip, which is transversely perforated at 38. This strip of connected price tickets has its rear surface coated with the cement 36 and this rear surface is covered by a backing sheet 39, such as waxed paper, which is continuous since the perforations do not extend through the same. This will permit of the separation of the individual price tickets 31 and removing the backing sheet 39 from the same. This provides a convenient method of handling the price tickets prior to

their application to the molding. After the tickets have been applied to the molding and separated therefrom or from each other they may be returned to the backing sheet 39, which will cover the adhesive.

It is to be understood that the forms of my invention herewith shown and described are to be taken as preferred examples of the same and that various changes in the shape, size, and arrangement of parts may be resorted to without departing from the spirit of my invention or the scope of the subjoined claims.

Having thus described my invention, what I claim is:

1. A molding having holding devices near its longitudinal edges, a resilient strip mounted upon the molding and having its material near its longitudinal edges bent inwardly upon itself to provide longitudinal tongues disposed upon the rear face of the resilient strip, the edges of the strip being arranged within the holding devices and the tongues serving to space the rear face of the strip from the front face of the molding to provide a space at the rear face of the strip, the resilient strip having a smooth front face, and a flexible price ticket having a character upon its front face and having its rear face provided with a pressure-sensitive adhesive for releasably attaching the rear face of the ticket to the smooth front face of the strip, the resilient strip being adapted to be depressed into the space for separating the ticket from the strip.

2. A molding having longitudinally extending holding devices, a resilient strip mounted upon the molding and having its longitudinal edges held within the longitudinal holding devices, a front sheet formed of a plastic which is dense and smooth, said front sheet being mounted upon the outer face of the resilient strip and having a width greater than the width of the strip and having its longitudinal edges bent about the longitudinal edges of the resilient strip for affording tongues arranged upon the inner face of the strip, said tongues serving to retain the resilient strip spaced from the face of the molding, price tick-

ets, each price ticket including an inner sheet, each inner sheet having a main character upon its front face and designating character or characters upon its front face, an outer sheet 5 formed of a plastic which is dense and smooth and secured to the front face of the inner sheet, each inner sheet having its rear face provided with a pressure-sensitive adhesive extending over substantially the entire area of such rear face, 10 one ticket being arranged in overlapping relation with the other ticket to cover the designating character or characters of the same, the pressure-sensitive adhesive of the front ticket serving to releasably secure such ticket to the smooth 15 dense outer sheet of the rear ticket throughout substantially the entire vertical dimension of the rear ticket so that the tickets are retained assembled adjacent to their top and bottoms, the assembled tickets being mounted upon the 20 smooth dense front sheet of the resilient strip and releasably secured to the same by the pressure-sensitive adhesive upon the rear face of the tickets.

3. A ticket holding device having longitudinal flanges which overhang the face of such device, said flanges having grooves beneath them, a resilient strip to be arranged upon the ticket holding device and having its longitudinal edges inserted within the grooves, said resilient strip having its material bent upon itself at said longitudinal edges to provide resilient tongues which are disposed upon the rear face of the resilient strip and thereby leaving the front face of the resilient strip free from projections adjacent to said longitudinal edges, and tickets disposed upon the front face of the resilient strip and having their longitudinal edges inserted within the grooves, the resilient tongues, longitudinal edge portions 35 of the resilient strip, longitudinal edge portions 30 of the tickets, and the flanges being disposed in overlapping relation so that the combined resilient actions of the strip and tongues serve to hold the tickets upon the flanges against improper displacement.

GEORGE H. TAYLOR.
